Lodi

[11] Patent Number: Des. 432,405

[45] Date of Patent: ** Oct. 24, 2000

[54] **WIRE ROUTING DEVICE WITH A KEYSLOT LOCKING BASE**

3,702,612 11/1972 Schlesinger .
5,219,134 6/1993 Morita et al. .

[75] Inventor: **Frank Lodi**, Niles, Ill.

Primary Examiner—B. J. Bullock
Attorney, Agent, or Firm—Martin Faier; Faier & Faier, P.C.

[73] Assignee: **Richco, Inc.**, Chicago, Ill.

[57] **CLAIM**

[**] Term: **14 Years**

The ornamental design for a wire routing device with a keyslot locking base, as shown and described.

[21] Appl. No.: **29/107,966**

DESCRIPTION

[22] Filed: **Jul. 16, 1999**

FIG. 1 is a perspective view of a device embodying the invention.

[51] LOC (7) Cl. **08-08**

FIG. 2 is a front elevational view of a device embodying the invention.

[52] U.S. Cl. **D8/395**; D8/396

FIG. 3 is a rear elevational view of a device embodying the invention.

[58] **Field of Search** D8/356, 395, 396;

FIG. 4 is a top view of a device embodying the invention.

D13/154, 199; 248/68.1, 73, 74.2, 220.41,
220.12, 220.11, 222.41, 316.7; 174/164

FIG. 5 is a bottom view of a device embodying the invention; and,
